CLAIM

The ornamental design for a display screen with a graphical user interface, as shown and described.

DESCRIPTION

FIG. 1 is a front view of a display screen with a graphical user interface showing an image in a transitional sequence according to our new design; and, FIG. 2 is a front view of the display screen with the graphical user interface showing another image in the transitional sequence according to our new design.

The outer broken lines showing the display screen form no part of the claimed design. The remaining broken lines showing text form no part of the claimed design.

The appearance of the transitional image sequentially transitions from the image of FIG. 1 to the image of FIG. 2. The top edge of the partial rounded rectangle remains stationary and provides a common point of reference between FIGS. 1 and 2. The partial rounded rectangle extends downward in the transition from FIG. 1 to FIG. 2, providing space for the additional graphical elements shown in FIG. 2. The pill shaped element also moves downward and maintains the same spacing between itself and the partial rounded rectangle in FIG. 2 that exists in FIG. 1. Furthermore, the pill shaped element below the partial rectangle decreases in width such that the width is narrower than that of the partial rounded rectangle. The process or period in which one image transitions to another image forms no part of the claimed design.

1 Claim, 2 Drawing Sheets
